G. JACKSON.
Knitting Mach.

No 11,554

Patented Aug. 22, 1854.

UNITED STATES PATENT OFFICE.

GEORGE JACKSON, OF COHOES, NEW YORK.

KNITTING-MACHINE.

Specification of Letters Patent No. 11,554, dated August 22, 1854.

To all whom it may concern:

Be it known that I, GEORGE JACKSON, of Cohoes, in the county of Albany and State of New York, have invented new and Improved Apparatus for the Construction and Operation of Warp Knitting-Looms; and I declare the following specification, with the drawings hereto attached as part of the same, to be a full and perfect description thereof.

Figure 1 represents a perspective view of the machine, a portion of the presser bar being removed to show the needle bar and needles behind it. Fig. 2 is a section showing the construction and arrangement of the sinkers bar, the presser bar, the needle bar and the thread carrier bar, with the sinkers, pressers and thread carriers. Fig. 3 4 and 5 show the forms of the cams on the shaft of the machine.

Similar letters in the different drawings denote the same parts of the apparatus.

The machine is a rectangular frame in the usual form of the knitting loom, as shown in Fig. 1 AAAA. Attached to the inner faces of the front legs or supports are two guides *w*, *w*, intended to receive and direct the vertical movement of the frame *Z* which carries the sinker and presser bars. This frame is made of two loops or clamps within which the ends of the pressure bar *C'* and sinker bar *C²* pass and operate; the bar *C²* being fastened at the bottom of each loop and *C'* being movable and adjustable, as to its distance from *C²* by the screws *RR* passing through the tops of the loops. Directly behind the bar *C²* with its upper surface raised somewhat above the upper surface of *C²* is the needle bar *D* extending across the frame, which has a forward and backward motion within horizontal guides attached to the upper bars of the frame work of the machine. These bars (so called) are rectangular metal bars or rods to which are attached certain parts of the apparatus, which gives name to the bar itself, to wit; the bar *C'* has attached to it and hanging down, a series of small oblong blocks *b*, *b*, slightly separated from each other, their lower edges, which range horizontally with each other, being rounded from front to rear to fit them for their duty, which is to press down the needle-bars as hereinafter described hence called the pressers, and their support the presser bar. The bar *C²* has attached to and rising from it, the sinkers (so called) which are small blocks *d*, *d*, equal in thickness of

face to the pressers, and placed opposite to them, carrying between each pair of blocks, a sinker which is, a thin slip of metal *o* having two teeth in the front upper edge as shown in Fig. 2 the upper tooth *o* being slightly acute, the other *2*, being hook shaped. The upper edge of these slips pass up, into the presser bar between the blocks, where they have a liberty of motion as the block *C'* is screwed up or down.

The bar *D* has attached to its upper surface a series of needles *e*, *e*, which project forward horizontally one between each sinker. These needles have a barb in their upper edge, being of the kind well known, and used on all knitting machines. Close in front of and in range with the needles is the thread-carrier bar. This is a rod or bar *X* whose ends pass through sockets in brackets *EE* attached to the side of the machine. This rod has attached to it at certain intervals, depending upon the nature of the fabric to be knit, metal sockets or guides *t*, *t*, called the thread-carriers shaped as shown in the drawings, being a sort of tubes, through which the threads, used in the work pass from spools *S*, and are directed along and between the needles during the knitting process. In order to direct the movement of the carrier the rod has a horizontal sliding motion, also a rocking motion on its axis. The spools *S*, required to hold the thread may be placed in any convenient position, to supply each carrier, a convenient arrangement is shown in Fig. 1 where one spool is shown in place.

The necessary movements are given to the different parts of the machine by the following apparatus. The wheel *O* is driven by belt or gearing from the main shaft of the factory. Near the extremity of its axle *G* it has two cam wheels *H*, *H*. On the outer face of each wheel a grove or slot-track cam (whose form is shown in Fig. 3) is made, into whose grooves operate the ends of levers *h*, *h*, by which the needle bar *D* is moved back or forth. On the inner face of each wheel is a cam whose form is shown at Fig. 4 and which operates upon a lever *I* passing under the lead and sinker frame and by which it is raised, the frame falling by its own weight. The sliding and rocking motion of the thread-carrier bar is produced thus: The rocking motion, by a slot track cam on the inner face of wheel *O*, (whose form is shown in Fig. 5) operating on the end of lever *V* pivoted on the crank *v*. The

sliding movement is produced by a cam *y* which projects from the inner face of a wheel *M*, its elevations and depressions from the face of the wheel, being arranged to produce the needful movements of the thread carriers in correspondence with the movements of the other parts of the knitting apparatus. A spring *P* keeps the rod steadily pressed against the cam *y*. The movement 10 of wheel *M* is produced by its gearing into a pinion wheel *N* on the outer end of shaft *G*.

The process of knitting by the machine is as follows: The apparatus being placed in such point of its movements, that the 15 thread-carriers are on the extreme right hand of their course and ranging above the line of needles. The wheel *O* is set in motion when the thread carrier moves to the left past three needles and then drops down 20 below their range, the thread being laid over the needles by this operation. The pressers and sinkers now descend and simultaneously the needles draw back, by which the thread is passed under the barbs of the needles, the 25 front teeth of the sinkers drawing the thread downward, to give the proper length of stitch, while the pressers close the needle-barbs. The needles continue to recede the thread being pressed forward by the sinkers, 30 until it reaches the end of the needle; then the sinkers and pressers rise, so as to permit the back teeth of the sinkers to rise over the stitch, the sinkers and pressers then descend, the needles coming forward at the 35 same time, by which each stitch is carried by a back tooth, back of the needle barbs at the same time the carriers descend taking the thread below the line of the needles, move past one needle to the left, and then 40 rise again above the range of needles, carrying the thread around the needles and making a stitch; at the same time the sinkers and pressers rise. The sinkers and pressers now stand still, while the thread-carriers 45 move to the right over three needles, when the carrier drops down, and operations similar precisely to those described take place, to wit: The sinkers drop down, the thread passes under the needle barbs, the needles 50 draw back, the pressers hold the barbs closed while the sinkers press the stitch, formed by the previous movements, over the ends of the needles and drop them over the threads or stitches which lie under the barbs. 55 The sinkers and pressers then rise, the needles come forward, the last made stitches are carried back of the barbs, the first stitches hanging down from them and forming the commencement of the cloth. The 60 carriers descend, carry the thread to the right under a needle, then with the sinkers and pressers rise to the position from which the machine first started. These operations are repeated till the work is completed.

It will be seen, that as the thread is carried, first over three needles to the left, and three stitches made, then under one needle further to the left and another stitch made. Then back over three needles to the right and three stitches made, then under one 70 needle farther to the right and another stitch made; a chain or loop stitch will occur at every change of motion of the thread-carrier from right to left, or left to right—this stitch forms a rib in the fabric. 75

The difference between my machine, and existing machines, and its advantages over them, I consider to be, as follows. In all warp knitting machines now used, each needle requires its separate thread, and in order to make ribbed or fancy work two sets or tiers of needles with their thread-carriers are required, each set having distinct and different movements, and being operated by their own separate wheels, cams, and levers. My machine requires but one set of needles by which ribbed and fancy work may be executed in every variety of style, simply by changing the form of the cam *y* that shifts the thread carrier to the right and left so as to move the thread over and under a greater or less number of needles at each separate movement, combined with a change in the proportions of the wheels *N* and *M*, which regulates the 95 movement of the pressers, sinkers, and needles. In the ordinary machine to change the character of the fabric, requires almost an entire change in all the arrangements for the movements of the machine. 100

In the present warp knitting machines the sinkers and pressers operate distinctly and separately from each other, and require distinct arrangements of the apparatus to drive them. In my machine the sinkers and pressers operate together, being in one frame. Also in those machines using as they do a separate thread to each needle, it becomes necessary to rewind the yarn from the spinning jacks (spools) upon a beam as long as the range of needles, from which beam the threads are taken to each carrier; this rewinding is called warping the yarn. 105 110

In my machine the spools are placed at once on the loom, and the threads taken from them to the carriers. 115

I claim—

The arrangement and combination of the pressers *b b* and sinkers *o o* in the frame *Z* in the manner substantially as described; whereby the pressers and sinkers move together and can be adjusted at such a distance apart as may be requisite to graduate the size of the stitches as required. 120

GEORGE JACKSON.
